UNITED STATES PATENT OFFICE.

HUGH H. PARKHILL, OF CHICAGO, ILLINOIS.

HEAD-REST.

SPECIFICATION forming part of Letters Patent No. 389,938, dated September 25, 1888.

Application filed May 4, 1888. Serial No. 272,842. (No model.)

To all whom it may concern:

Be it known that I, HUGH H. PARKHILL, a citizen of the United States, residing at Chicago, in the county of Cook and State of Illinois, have 5 invented certain new and useful Improvements in Head-Rests, of which the following is a specification.

My invention relates to portable head-rests, particularly for the use of travelers in rail-way-cars, or for use at home on chairs or lounges, as may be required for invalids or others.

The objects of my invention are to provide a portable head-rest that may be easily engaged with or disengaged from the back of a car-seat, chair, sofa, or other article of furniture, that may be easily adjusted and secured at any desired angle to suit the occupant, and that is convenient to carry in a small compass 20 when not in use. These objects I attain by the mechanism shown in the accompanying drawings, in which—

Figure 1 is a side elevation of my improved head-rest attached to the back of a car-seat, S. 25 Fig. 2 is a view of the back part of the head-rest and a part of the supporting-rod. Fig. 3 is a transverse section through the clamping-bolt and its socket, taken on the line $x-x$ of Fig. 1. Fig. 4 is a side elevation of clamping-bolt in 30 its normal position when in use. Fig. 5 is a similar view of the clamping-bolt, taken at right angles to Fig. 4, or at a quarter-turn from said figure. Fig. 6 is a view of inside of the outer clamping-jaw and socket for clamp- 35 ing bolt or screw.

Similar letters refer to like parts in all the figures.

A is the head-rest proper. It is constructed as follows: An arm, a , projects from a circular hinge-plate, b , and is provided at its outer end with two head-rest cushion-bearing plates, $c c$, hinged together at the outer end of arm a . On plates c are secured cushions d , in the usual well-known manner. Plates $c c$ may be rigidly attached to arm a instead of being hinged, as both these constructions are common in head-rests.

B is the head-rest-tilting device, which consists of the following parts: b is a circular plate 50 provided with radial perforations on a part of its periphery, as shown by dotted lines in Fig. 1. Said perforations are screw-threaded at their

bottoms to receive a regulating spring supported pin, e . (Shown in Figs. 1 and 2.) Plate b is centrally perforated to receive pivotal set-screw f . From plate b the supporting-rod g depends, as shown in Figs. 1 and 2. h is the twin hinge-plate of b , fitting against it and pivotally secured thereto by thumb-screw f . i is an overhanging flange portion of h , perforated radially to receive pin e , which is secured to spring j . By this arrangement the head-rest may be tilted to any desired angle and secured in such position by simply turning spring-supported pin e and set-screw f . 65

By threading only the lower portion of pin e , I am enabled to obtain a strong support for the head-rest without danger of breakage to pin e , the strain against the pin being confined to its upper smooth unthreaded portion, which 70 will give the increased strength of resistance to breakage above referred to.

C is the clamping device. It consists of two opposing clamping-jaws, $k l$, and a clamping-bolt, D. The outer clamping-jaw, k , is a broad 75 plate provided with a socket portion, m , at right angles to its upper part, as shown in Figs. 1 and 6. The socket n is of circular form, having its entrance partially cut off or blocked up by a plate, o , equal in thickness to the 80 spaces between the threads of clamping-bolt D, which will presently be described. Socket n extends nearly to plate k , as shown in dotted lines, Fig. 1. Clamping-jaw l may be similar in size, or narrower, if desired, than 85 outer jaw, k . It has a perforated collar or hub, l' , to receive the clamping-bolt.

D is the clamping-bolt, provided near its outer end with a socket, q , (adapted to receive supporting-rod g , before described,) and a set-screw, r , to secure rod g in any desired position. The body of bolt D is of the shape shown in cross-section in Fig. 3—i. e., of circular form with a segment cut off. It is also provided with a series of equidistant flanges 95 or threads, s , parallel to each other, and which may be at right angles to the axis of the bolt or oblique thereto.

In putting my device into use I first place bolt D with its flatsurface t parallel with the corresponding flat surface of plate o . The bolt or screw will then enter socket n . I then press plates $k l$ tightly together upon the back of the car-seat, chair, or sofa. By turning bolt D 100

about a quarter-turn the clamping device will be secured in place. I then insert rod *g*, secure it in place by set-screw *r*, and adjust the head-rest, as before described.

5 What I claim as new, and desire to secure by Letters Patent, is—

1. The combination of a head-rest with an adjustable tilting device consisting of a circular plate perforated radially from its periphery, 10 said perforations being screw-threaded at their bottoms, a rod, *g*, supporting the tilting device, a twin plate, *h*, provided with an arm, *a*, an overhanging flange, *i*, and a spring-supported

screw-threaded adjusting-pin, *e*, as herein set forth and described. 15

2. In portable head-rests, a clamping device consisting of jaws *k l*, one of which, *k*, is provided with a socket and a cut-off plate, *o*, as herein shown, and a clamping-bolt in cross-section a segment of a circle, provided with 20 equidistant flanges *s* and a socket, *q*, as and for the purposes herein set forth.

HUGH H. PARKHILL.
